A. R. SPIELBERGER.
FOUNTAIN COMB.
APPLICATION FILED SEPT. 12, 1918.

1.314.158.

Patented Aug. 26, 1919.

UNITED STATES PATENT OFFICE.

ABE R. SPIELBERGER, OF ATLANTA, GEORGIA.

FOUNTAIN-COMB.

1,314,158.

Specification of Letters Patent. Patented Aug. 26, 1919.

Application filed September 12, 1918. Serial No. 253,717.

To all whom it may concern:

Be it known that I, ABE R. SPIELBERGER, a citizen of the United States, residing at Atlanta, in the county of Fulton and State 5 of Georgia, have invented certain new and useful Improvements in Fountain-Combs; and I do declare the following to be a full, clear, and exact description of the invention, such as will enable others skilled in the art 10 to which it appertains to make and use the same.

This invention relates to combs and it relates more particularly to fountain combs.

The main object of this invention is to 15 generally improve upon the fountain comb described and claimed in my former patent, No. 1,256,386, issued February 12, 1918.

The advantages obtained by this present invention may be best emphasized by a statement 20 of the disadvantages experienced in connection with the device which is the subject matter of the patent above referred to, some of the disadvantages being as follows:

The ball 25 was found to be too expensive, 25 especially if made hollow, and it was too heavy when made solid. Moreover, this ball did not satisfactorily operate to collapse the tube 7 but would sometimes puncture or tear the tube and thus cause considerable 30 waste and annoyance. It was also found difficult to connect the two threaded connections of the handle with the back 5, because each of these threaded connections interfered with the other. Moreover, it was 35 found expensive and impracticable to form the racks 19 within the slots of the handle member, and the pinions of the gears 23 added to the expense.

The foregoing disadvantages and difficulties 40 are overcome by the simplified and practical construction which is disclosed in the accompanying drawings, in which:

Figure 1 is a side elevation of my improved fountain comb;

Fig. 2 is a top plan view;

Fig. 3 is a longitudinal vertical sectional view;

Fig. 4 is a horizontal longitudinal sectional view;

Fig. 5 is a transverse sectional view along the line of 5—5 of Fig. 1, and

Fig. 6 is a side elevation of my special dispensing tube detached.

Referring to these drawings, in detail, in 55 which similar reference characters correspond with similar parts throughout the

several views, this device consists of a combined combing and dispensing member 7, a hollow handle member 8, a rotary winding member 9, a ring or guiding member 10 and securing members 11, the latter being preferably in the form of thumb screws which may be quickly and easily removed and replaced without the use of tools.

The comb member 7 is provided with a 60 passage 12 which has outlets 13, and an inlet 14. This member 7 is formed with a hollow shank 15, the hollow of this shank comprising a frusto-conical cavity 16 and a cylindrical internally threaded cavity 17, 65 the latter being in open communication with the inlet 14 and the frusto-conical cavity 16. The purpose of the shape of the cavities 16 and 17, as specifically described in the foregoing, is to snugly and securely engage with 70 the dispensing end portion *b* of a collapsible tube *a* of special construction, that is, the improved collapsible tube (see Fig. 6) of soft metal which is employed as a receiving and dispensing receptacle for ointments, 75 pomades and the like. From an observation of Figs. 3 and 4, it will be seen that the tapering and screw-threaded end portion *b* fits snugly in the recesses 16 and 17, so that the member 7 is substantially integral therewith. Moreover, the shank 15 is formed with a shouldered seat 18 which is smooth and unbroken with the exception of apertures 19 which are screw-threaded to receive 80 the screws 11. These screws extend through 85 apertures of the hollow handle 8, and secure it to the seat 18. However, when it is desired to remove the handle 8, the screws 11 are removed, and the handle may then be removed by a relative longitudinal movement of the members 7 and 8. The handle 8 is preferably formed with perforations 20, and these perforations lighten the handle and also provide an anti-slipping engagement of the handle with the hand of the 90 user. Moreover, the handle 8 is formed with opposite slots 21 which extend longitudinally from one end portion to the other, but terminate short of the extremities of the handle.

The rotary member 9 is provided with a slot 22 which receives the flattened or collapsed end of the tube *a*, and a manipulative element 23 is provided on one end of the member 9, so that the collapsed end of the 105 tube may be wound upon this member by rotating the same. The end portions of the 110

member 9 extend through the slots 21 and through bearings in the member 10 which embraces and is slid able along the hollow handle. This guide 10 retains the member 5 9 substantially perpendicularly to the length of the handle during the winding and consequent collapsing of the tube, it being understood that the rotary member 9 moves laterally of its axis and longitudinally of 10 the slots 21 in consequence of the shortening of the tube during the winding and collapsing thereof. Obviously, as the tube is collapsed or flattened, it is proportionately broadened, and in order to provide for this 15 increase in breadth of the tube without adding unnecessary material and weight to the handle, the latter is preferably formed with an elliptical or oblong cross section, as indicated in Fig. 5. This not only obtains the 20 desired result mentioned, but insures accuracy and ease in adjusting the handle to the member 5 in such relation that the apertures which receive the screws 11 are accurately alined without special effort by the 25 user.

The rear end of the handle 8 is preferably open so as to allow the user to quickly and easily engage the collapsed end of the tube with the slot 22.

30 Although I have described this embodiment of my invention very specifically, it is not intended to limit this invention to these exact details of construction and arrangement of parts, but I am entitled to make 35 changes without departing from the inventive idea disclosed in the foregoing description and the following claims.

What I claim is:

1. In a fountain comb, the combination of 40 a collapsible dispensing tube having a long frusto-conical neck and an externally threaded end element on said neck, a combing and dispensing member provided with a passage having an inlet and outlets, said member 45 being formed with a long frusto-conical cavity and with a threaded seat in open communication with said cavity and inlet, whereby said combing and dispensing member is adapted to snugly and securely engage 50 with the frusto-conical and threaded end portions of said collapsible dispensing tube.

2. In a fountain comb, the combination of 55 a collapsible dispensing tube having a long frusto-conical neck and an externally threaded end element on said neck, a combing and dispensing member provided with a passage having an inlet and outlets, said member being formed with a long frusto-conical cavity, and with a threaded seat in open communication 60 with said cavity and inlet, said combing and dispensing member being adapted to snugly and securely engage with the frusto-

conical and threaded end portion of said collapsible dispensing tube, a hollow handle associated with said member and adapted to 65 receive the body of a tube thus engaged with said dispensing member, and means carried by said handle for forcing the contents of the tube through said inlet.

3. In a fountain comb, the combination of 70 a collapsible dispensing tube having a long frusto-conical neck and an externally threaded end element on said neck, a combing and dispensing member provided with a passage having an inlet and outlets, said member 75 being formed with a long frusto-conical cavity and threaded seat to receive the frusto-conical and threaded portions of said collapsible dispensing tube, said shank being formed with a seat that is non-cylindrical in 80 cross section and has threaded cavities therein, a hollow handle adapted to receive the body of the dispensing tube and having one end fitted around said seat, screws engaged with said handle and with said threaded 85 cavities to removably secure said hollow handle on said seat, and means carried by said handle for forcing the contents of the tube into said dispensing member.

4. In a fountain comb, the combination of 90 a collapsible dispensing tube, a combing and dispensing member having a cavity to receive the dispensing end of the collapsible tube, a hollow handle secured thereto and having opposite slots extending therealong 95 and a rotary member engageable with the other end of the dispensing tube and operable to wind the body of the tube thereon and thereby collapse the tube, said rotary member having its end portions extending 100 through said opposite slots and adapted to be drawn therealong by the tube when the latter is being thus wound.

5. In a fountain comb, the combination of 105 a collapsible dispensing tube, a combing and dispensing member having a cavity to receive the dispensing end of the collapsible tube, a hollow handle secured thereto and having opposite slots extending therealong, a rotary member engageable with the other 110 end of the dispensing tube and operable to wind the body of the tube thereon and thereby collapse the tube, said rotary member having its end portions extending through said opposite slots and adapted to be drawn 115 therealong by the tube when the latter is being thus wound, and means embracing the exterior surface of the handle and being effective to hold the axis of said rotary member perpendicular to the length of the handle while it travels along the handle.

In testimony whereof I have hereunto set my hand.

ABE R. SPIELBERGER.
